[57] CLAIM

The ornamental design for a electrical connector, as shown and described.

DESCRIPTION

FIG. 1 is a perspective view of a electrical connector in accordance with a preferred embodiment of the present invention;

FIG. 2 is a right side view of the electrical connector shown in FIG. 1;

FIG. 3 is a front view of the electrical connector shown in FIG. 1;

FIG. 4 is a top view of the electrical connector shown in FIG. 1; and,

FIG. 5 is a bottom view of the electrical connector shown in FIG. 1.

The electrical connector illustrated in the drawings is symmetrical about a central axis. Accordingly, a left side view is the same as the right side view of FIG. 2, and a rear view is the same as the front view of FIG. 3.
